CLAIM

The ornamental design for an over wheel well truck tool box, as shown and described.

DESCRIPTION

FIG. 1 is a perspective view showing the bottom front and right hand side of my over wheel well truck tool box;

FIG. 2 is a perspective view showing the front, left side and top of the tool box of FIG. 1;

FIG. 3 is a top plan view of the tool box of FIG. 1;

FIG. 4 is a bottom plan view of the tool box of FIG. 1;

FIG. 5 is a right side elevation view of the tool box of FIG. 1, the left side being a mirror image thereof as may be seen from FIG. 2;

FIG. 6 is a front end elevation view of the tool box of FIG. 1; and

FIG. 7 is a rear end elevation view of the tool box of FIG. 1.
